(57) **CLAIM**

The ornamental design for a container with lid, as shown and described.

DESCRIPTION

FIG. 1 is a front, side and top perspective view of the container with lid showing my new design;

FIG. 2 is a front elevational view thereof;

FIG. 3 is a right side elevational view, the opposite side being a mirror image thereof;

FIG. 4 is a rear elevational view thereof;

FIG. 5 is a top plan view thereof;

FIG. 6 is a bottom plan view thereof;

FIG. 7 is a front and side perspective view of a variation thereof with the handle mounted on the rear wall;

FIG. 8 is a rear elevational view of the variation of FIG. 7;

FIG. 9 is a front and side perspective view of another variation thereof without the handle;

FIG. 10 is a right side elevational view of the variation of FIG. 9, the opposite side being a mirror image thereof; and,

FIG. 11 is a bottom plan view of the variation of FIG. 9.
